TOILET CLOSET

Elsie Goodfield, Dover, N. J.

Application December 1, 1949, Serial No. 130,386

2 Claims. (Cl. 4—135)

1

This invention comprises novel and useful improvements in a toilet closet and more specifically pertains to an improved combination of a toilet bowl with a cabinet.

The primary object of this invention is to provide a convenient and improved concealed assembly of a toilet bowl with a cabinet structure whereby a more compact arrangement is obtained, whereby the toilet bowl is concealed when not in use and the space occupied thereby does not diminish the effective table space of the cabinet; wherein provision is made for such toilet accessories as a toilet brush and toilet paper rolls; and wherein generally a much more neat and attractive and unobtrusive arrangement of a toilet bowl is provided.

These, together with various ancillary features and objects of the invention which will later become apparent as the following description proceeds, are attained by the present invention, a preferred embodiment of which has been illustrated by way of example only in the accompanying drawings, wherein:

Figure 1 is a perspective view showing the improved cabinet having the toilet bowl forming the subject of this invention combined therewith, the device being in the toilet bowl concealing position of the same;

Figure 2 is a fragmentary perspective view of a portion of Figure 1, showing the toilet seat cover raised with the toilet bowl ready for use;

Figure 3 is a fragmentary perspective view similar to Figure 2 but showing both the toilet seat cover and the toilet seat raised whereby access may be had to a toilet brush container and a toilet paper roll container in accordance with this invention;

Figure 4 is a vertical transverse sectional view taken substantially upon the plane indicated by the section line 4—4 of Figure 3;

Figure 5 is a vertical sectional view taken substantially upon the plane indicated by the section line 5—5 of Figure 4 and showing in particular the arrangement and positioning of the containers for receiving the toilet brush and the toilet paper rolls;

Figure 6 is a fragmentary vertical transverse sectional view taken substantially upon the plane indicated by the section line 6—6 of Figure 4 and illustrating the manner in which the toilet bowl is adapted for mounting upon the floor supporting the cabinet; and

Figure 7 is a perspective view, part being broken away, of the toilet brush container forming the subject of this invention.

2

Referring now more specifically to the accompanying drawings, wherein like numerals designate similar parts throughout the various views, the numeral 10 refers generally to a cabinet in which has been combined a toilet bowl in accordance with the principles of this invention. The cabinet may conveniently comprise an upper section 12, provided with customary drawers and doors to provide a plurality of storage compartments as desired, together with a base section 14 which, in turn, is provided with a plurality of storage drawers and doors, and has a horizontal cabinet or table surface 16, together with a front surface 18.

Intermediate its ends, the lower portion 14 of the cabinet assembly is provided with a chamber opening through the front and top walls of the cabinet, and this chamber receives and houses a porcelain or other toilet bowl 20 which is of any known design or construction, but preferably, is of square or cubical shape. For this purpose, the front surface of the toilet bowl 20, as indicated at 22, lies in a vertical plane and thus forms a flush continuation of the vertical plane 18 of the lower cabinet member 14; while the top surface of the toilet bowl 24 lies in a horizontal plane which extends substantially entirely between the two sides of the recess or chamber in the cabinet, and which is disposed slightly below the plane of the surface 16 of the cabinet. Pivoted to the toilet bowl 20 in any convenient manner, as indicated at 26, is a conventional toilet seat 28 which is of sufficient size to snugly fit within the space between the two side walls of the chamber of the cabinet lower section 14, while a toilet seat cover 30 is, in turn, hinged to the toilet seat 28 as at 32, this cover in its lowered position constituting a complete closure for the chamber, and forming a smooth continuation of the upper surface 16 of the lower cabinet member 14.

Adjacent its rear face, the toilet bowl 20 is provided with a pair of vertical bores or recesses 34 and 36 which open downwardly from the upper end thereof, and are positioned to be closed by the toilet seat 28 in the lowered position of the latter as shown in Figure 2, and to be uncovered by the toilet seat in the raised position of the same, as shown in Figure 3.

One of these bores or recesses such as that indicated at 34 is adapted to detachably receive a container 38 which is preferably in the form of a sleeve of thin sheet metal or the like, which has an annular outward flange 40 at its upper 55 end by means of which the sleeve may be sup-

ported upon the upper surface of the toilet bowl and retained therein. At its lower end, the container is closed as shown at 42 in Figure 5, and its side walls adjacent the lower end are provided with suitable ventilating openings or apertures 44. Disposed within the container 38 and adjacent the upper end thereof, is an inwardly extending hook 46 by means of which a toilet brush or the like, such as that indicated at 48 may be supported and detachably mounted in the container. Thus, the container serves to house and conceal a toilet brush, and the closed lower end of the same will retain moisture dripping from the bristles of the brush; while the ventilating apertures will serve to admit flow of air for ventilating purposes. The container 38 may be removed or inserted in the recess 34 as desired.

The other recess 36 is adapted to detachably receive a cage 50 which if desired may be of similar construction to the container 38 and which likewise is supported in the recess as by an annular external flange 52 at its upper end. This cage is adapted to contain a plurality of toilet paper rolls such as those indicated at 54, and these rolls may be conveniently carried by a support rod 56 having a head or knob portion 58, which rod has a head portion 60 at its lower end underlying the lowermost of the paper rolls 40. The arrangement is such that paper rolls may be dropped upon the upper end of the rod, and stacked thereon, whereupon the rod may be inserted in the cage 50, and the cage itself may be detachably received in the recess 36.

Conveniently, the flush tank 62 for the toilet bowl, may be mounted in the upper cabinet portion 12, and may be of any desired construction, having a discharge pipe 64 connecting this tank with the toilet bowl in the customary manner. All the necessary plumbing may thus be mounted and enclosed within the cabinet 10, and thereby concealed, while the toilet flush control 66, see Figures 1, 2 and 3, may extend through the upper cabinet structure 12.

The toilet bowl may be mounted within the cabinet structure in any desired manner, and as shown in Figures 4, 5 and 6, is intended to rest upon the floor which supports the cabinet, and to substantially completely fill the space of the chamber in the lower cabinet section 14. Conveniently, as shown in Figure 6, the side walls of the toilet bowl may be laterally recessed or notched, as at 68, and suitable anchor bolts 70 may be mounted in the floor 72, extending into this recess and being provided with fastening nuts 74.

From the foregoing, it will be seen that a toilet closet has been provided which by virtue of its substantially cubical shape is of exceptional com-

pactness, durability and strength may be readily housed within a cabinet structure for compact and concealed association therewith, and whereby the entire upper surface of the cabinet is available as a desk space.

From the foregoing, the construction and operation of the invention together with its many advantages will be readily apparent and further explanation is believed to be unnecessary. However, since numerous modifications and changes will readily occur to those skilled in the art after a consideration of the foregoing specification and accompanying drawings, it is not desired to limit the invention to the exact construction shown and described, but all suitable modifications and equivalents may be resorted to, falling within the scope of the appended claims.

Having described the invention, what is claimed as new is:

20 1. A toilet closet comprising a cabinet having a top, a chamber in said cabinet, a cover for said chamber forming a continuation of the top of said cabinet, a toilet bowl mounted in said chamber beneath said cover, said toilet bowl having a pair of vertical recesses therein at opposite sides thereof, a container received in each recess for holding a toilet article, and a seat for said bowl beneath said cover closing said containers.

30 2. A toilet closet comprising a cabinet having a top, a chamber in said cabinet, a cover for said chamber forming a continuation of the top of said cabinet, a toilet bowl mounted in said chamber beneath said cover, said toilet bowl having a vertical recess, a container received in said recess for holding a toilet brush, said container having ventilating openings in its walls, a support flange at its upper end and a brush supporting hook, and a seat for said bowl beneath said cover closing said container.

40 ELSIE GOODFIELD.
